GLENDALE, CALIFORNIA

SIGNAL-LIGHT SWITCH

Application filed January 2, 1929. Serial No. 329,893.

This invention relates to electric lights, the primary object of the invention being to provide an electric light so positioned that the arm of the operator of the motor vehicle 5 equipped with the light, will be automatically illuminated when the operator extends his arm to make a signal on turning.

An important object of the invention is to provide a switch controlling bar so constructed that it will be engaged by the arm of the operator when the operator extends his arm laterally in making a signal, thereby insuring the completing of the circuit to the electric lamp.

15 A still further object of the invention is to provide a switch controlling bar of such construction that it will be actuated by the operator's arm regardless of the angle at which the operator's arm is extended in making the 20 signal.

With the foregoing and other objects in view which will appear as the description proceeds, the invention resides in the combination and arrangement of parts and in the 25 details of construction hereinafter described and claimed, it being understood that changes in the precise embodiment of the invention herein disclosed, may be made within the scope of what is claimed, without departing 30 from the spirit of the invention.

Referring to the drawings:

Figure 1 is a perspective view indicating an electric lamp and switch actuating mechanism, constructed in accordance with the 35 present invention.

Figure 2 is an enlarged view illustrating the inner side of the lamp casing.

Figure 3 is a front elevational view of the lamp casing.

40 Figure 4 is a sectional view taken on line 4-4 of Figure 2.

Figure 5 is a sectional view taken on line 5-5 of Figure 2.

Figure 6 is a sectional view taken on line 45 6-6 of Figure 5.

Referring to the drawings in detail, the device includes a cylindrical lamp housing 5 which has its side cut away as at 6 defining an opening throughout the length thereof, through which light rays from a lamp

supported within the casing, may be projected.

This casing 5 is supported by means of the bands 7, that embrace portions of the casing, the bands being secured to a supporting surface, and in the present showing these bands are supported adjacent to the door opening at the top of the door, the casing being arranged in such a way that the opening is directed downwardly and outwardly.

In one end of the casing 5 is a lamp socket 8 in which the lamp 9 is secured, there being provided wires 10 and 11 providing the circuit between the lamp and a suitable 65 source of electricity supply. As shown, these wires lead to the contacts 12 and 13 of the switch 14 which switch includes arms 15 that are carried by the bar 16 which slides through the switch housing, 70 the ends thereof extending beyond the ends of the switch housing, as clearly shown by Figure 2 of the drawings.

Forming an important feature of the invention is the switch actuating bar 17 that 75 is pivotally connected to the door frame, by means of the bolt 18, the upper end of the bar being formed with a notch to receive one of the ends of the bar 16, so that movement of the bar 17, in one direction, will 80 result in a movement of the bar 16 to cause the arms 15 supported thereby to engage the contacts 12 and 13 and complete the circuit to the lamp 9.

The bar 17 is curved outwardly so that it 85 extends beyond the rear edge of the window opening of the door with which the device is used so that a person extending his arm through the window in the act of giving a signal, will, by contact of his arm with the bar 17, force the lower end of the bar 17 rearwardly and move the upper end of the bar to operate the switch and complete the circuit.

A coiled spring 19 forms a part of the 90 switch and acts to return the bar 16 to its normal position, it being obvious that when the bar 16 is returned, the bar 17 will also be moved to its inactive position.

In order that the bar 17 will be except- 100

tionally sensitive to the movements of the operator's arm, the lower end of the bar 17 is extended at right angles and passed through the guide 20 in the form of a clip secured to the door frame.

5 It might be further stated that a supporting plate 21 is provided on which the bar 17 and switch are secured so that the mechanism may be readily and easily positioned by persons unfamiliar with mechanics.

10 From the foregoing it will be obvious that due to the construction shown and described, a person extending his arm, will operate the bar to complete a circuit to the lamp which in turn will project light rays onto the extended arm, illuminating the arm to the end that the arm will be clearly visible in the dark.

15 We claim:

20 In a device of the class described, a bar pivotally mounted adjacent to the window of a vehicle, said bar having an outwardly curved lower section extending into the window opening, and extending from a point adjacent to the upper end of the window, 25 terminating at a point adjacent to the lower end of the window, said bar having a right angled lower end, a guide through which the right angled lower end passes, and an electric switch actuated by the bar.

30 In testimony that we claim the foregoing as our own, we have hereto affixed our signatures.

CHARLES F. NICKELL
RANDSOME M. NICKELL.
35 HARRY E. NICKELL.
